UNITED STATES PATENT OFFICE.

FREDERICK WESTERMAN, OF CHICAGO, ILLINOIS.

DEPOSITING-MACHINE.

1,121,433.

Specification of Letters Patent. Patented Dec. 15, 1914.

Application filed February 7, 1914. Serial No. 817,313.

To all whom it may concern:

Be it known that I, FREDERICK WESTERMAN, a citizen of the United States, and a resident of the city of Chicago, county of Cook, and State of Illinois, have invented 5 certain new and useful Improvements in Depositing-Machines, of which I do declare the following to be a full, clear, and exact description, reference being had to the accompanying drawings, forming part of this 10 specification.

The present invention has relation more particularly to that class of depositing machines designed for depositing marshmallow and other confections upon the upper 15 surface of cakes that are fed in successive rows beneath the depositing mechanism. An example of this type of machine is set forth in an application for letters patent 20 filed by me in the United States Patent Office May 29, 1911, Serial No. 630,268, and in an application filed by me in the Patent Office December 20, 1913, Serial No. 807,851.

The invention constituting the subject- 25 matter of the present application relates particularly to the mechanism for controlling the passage of the marshmallow or other confections to the cakes or other surface on which such confections are to be deposited, and the invention consists in the 30 features of novelty hereinafter described, illustrated in the accompanying drawings and particularly pointed out in the claims at the end of this specification.

Inasmuch as the mechanism for advancing the cakes or like articles beneath the depositing mechanism and the means for actuating the plungers whereby the confections are advanced from the receptacles containing 35 the same are the same as set forth in my above mentioned application Serial No. 807,851, it is not deemed necessary to fully illustrate such mechanism, nor is it necessary to illustrate all the actuating mechanism 40 whereby the operation of the valves hereinafter described is effected, as such omitted mechanism is fully embodied in my said application Serial No. 807,851.

Figure 1 is a view in vertical section on 45 line 1—1 of Fig. 4. Fig. 2 is a detail view in vertical section on line 2—2 of Fig. 1. Fig. 3 is a detail view in horizontal section on line 3—3 of Fig. 1. Fig. 4 is an enlarged view in vertical cross section, this 50 view being taken centrally through Fig. 1. Fig. 5 is an inverted or bottom view of the

depositing mechanism, parts being shown in section and parts being broken away. Fig. 6 is an enlarged detail view through the depositing mechanism, the valve mechanism 60 being shown in open position. Fig. 7 is a view in horizontal section on line 7—7 of Fig. 6. Fig. 8 is a detail perspective view showing a cake upon which deposits of confection have been made by the improved 65 mechanism herein set forth.

An endless carrier 10 supported upon a vertical movable table 11 may be employed for intermittently moving the rows of cakes upon the tops of which the deposits of 70 marshmallow, chocolate or like confection will be made. This carrier belt and table and the mechanism for operating the same may be such as set forth in my hereinbefore mentioned application, Serial No. 807,851 75 and need not, therefore, be more fully described.

Above the carrier 10 and suitably supported by the main frame of the machine are the receptacles 15 and 16 that will contain, respectively, the marshmallow and chocolate or like confections that are to be deposited. Beneath the receptacles 15 and 16 is a casting 17 suitably supported from the main frame and having cylindrical openings extending from end to end, within which cylindrical openings are mounted the two cylindrical plunger carriers 18 and 19. These plunger carriers 18 and 19 are provided respectively with plungers 20 and 21 by which, 80 as the plunger carriers are intermittently rotated, the confections will be discharged through channels 22 and 23 leading through the lower part of the casting 17. The construction and function of the plunger carriers are the same as in the machine illustrated and set forth in my said application 85 Serial No. 807,851 and need not, therefore, be more fully described.

From end to end of the lower part of the 90 central portion of the casting 17 extend dovetailed channels or chambers within which are mounted, in manner free to reciprocate, the slide valves 25 and 26, these valves being located upon opposite sides of 95 the division wall forming part of the casting 17. These slide valves serve to control the passage of confections through the channels 22 and 23, respectively. Each of these slide valves 25 and 26 is formed with a series 100 of channels 27 (see Fig. 5), these channels being adapted to be brought successively op-

posite ports in the top plate of a chambered casting 30. This chambered casting 30 is located beneath the central portion of the casting 17 and the longitudinal edges of the casting 30 are preferably beveled to form at one side a dovetail engagement with a flange 17^a and at the opposite side to engage a beveled bar 31 formed at the inner side of an adjustable plate or casting 32. The means for retaining the chambered casting 30 in position beneath the casting 17 is fully set forth in my above mentioned application Serial No. 807,851.

Over the top of the chambered casting 30 extends a cover plate 35 that is held by screws within the recessed upper portion of the casting 30. In this cover plate are formed a series of holes corresponding in number and arrangement with the channels 27 in the slide valves 25 and 26. Within one set of these holes in the cover plate 35 are fixed the upper ends of the short pipes 36, the lower ends of which enter corresponding holes formed in a plate or diaphragm 37 that extends beneath and parallel with the cover plate 35. This plate or diaphragm 37 is arranged at a sufficient distance from the cover plate 35 to form a chamber 38 for the flow of confection (admitted by the ports 38^a to the chamber 38) to the series of delivery pipes 39.

Inasmuch as my present invention in its preferred form is designed to make upon each cake a series of deposits of marshmallow or like confection coated with chocolate or the like, in the manner illustrated in Fig. 8 of the drawings, the delivery pipes 39 are concentrically arranged, as shown, and the lower end of each of these delivery pipes 39 extends downward and terminates at a slight distance above a corresponding series of discharge openings 40 that are formed in the bottom plates 41 that are set within a series of bottom openings extending from end to end of the chambered casting 30. These bottom plates 41 are preferably formed of sheet metal and shaped each with an annular channel in which the openings 40 are formed, and, as shown, each bottom plate 41 is provided with a flanged upper edge 42 that engages the bottom of the casting 30 (see Figs. 4 and 6).

Within the chamber 45 formed in the casting 30 beneath the plate or diaphragm 37, and surrounding the delivery pipes 39, are arranged the tubular valves 46, each of these valves setting around a corresponding delivery pipe 39. These valves 46 are arranged in annular groups or series corresponding to the arrangement of the delivery pipes 39, and the upper end of each of the tubular valves 46 is fixed within a hole formed in an annular ring or valve carrier 47. Each of the annular valve carriers 47 is provided with a trunnion 48 that sets

within a socket formed in a rocking arm 49 that is fixed to a valve shifting rock shaft 50. Upon this shaft 50 are arranged spacing sleeves 51 between the hubs of the rocking arms 49.

The slide valves 25 and 26 will be actuated by the mechanism shown in my above mentioned application Serial No. 807,851. To one end of the slide valve 25 is connected a crank 60 secured to the upper end of a rod 61 and to the lower end of this rod 61 is fastened a crank 62 through which passes a bolt carrying a roller 63 that sets within a cam groove 64 of a cam wheel 65 mounted on the shaft 66. Similarly, one end of the valve 26 is connected to a crank 67 at the upper end of the rod 68, the lower end of this rod being provided with a crank 69 through which passes a bolt provided with a roller 70 that travels in the cam groove 71 of a cam wheel 72 on the shaft 73. Hence, it will be seen that as the shafts 66 and 73 are rotated, as by mechanism set forth in my above mentioned application Serial No. 807,851, a reciprocating movement will be imparted to the valves 25 and 26.

The mechanism for operating the valve shifting rock shaft 50 is substantially the same as that set forth in my above mentioned application Serial No. 807,851. That is to say, one end of the shaft 50 projects through the end wall of the chambered casting 30, and to this projecting end of the shaft 50 is connected a crank arm 75, the opposite end of this crank arm 75 being attached to a pin 76 projecting from the head or nut 77 fixed to the upper end of a shifting rod 78. The lower end of this shifting rod 78 is pivotally connected to a rock arm 79 (see Fig. 2), one end of which rock arm is pivoted to a stud 80 projecting from the main frame, while the opposite end of the rock arm 79 carries a roller 81 that rides upon the periphery of a cam wheel 82 that is adjustably mounted upon a shaft 83.

From the foregoing description it will be seen that marshmallow or like confection from the receptacle 15 will be forced by the plunger 20 through the channel 22, the ports or openings 38^a and into the chamber 38. Thence, it will pass through the delivery pipes 39. At the same time chocolate or like confection from the receptacle 16 will be forced by the plunger 21 through the channel 23 and through the tubes 36 into the chamber 45 of the casting 30 and from this chamber 45 it will flow through the discharge ports or openings 40 and around the streams of marshmallow passing through the delivery pipes 39. The slide valves 25 and 26 will serve, as in my before mentioned application Serial No. 807,851, to primarily control the flow of marshmallow and chocolate or like confections through the channels 22 and 23, while the flow of the chocolate or

like confection, with which the marshmallow is coated, will be controlled at the discharge openings 40 by means of the tubular valves 46. It will be observed that each of these 5 valves 46 is of slightly greater diameter than the discharge opening 40 beneath it, so that when the valves 46 are lowered (as seen in Fig. 4) they will close the space between the bottom plate 41 and the lower ends of the 10 delivery pipes 39 thereby cutting off the flow of chocolate around the marshmallow. Hence, it will be seen that with the concentric arrangement of the delivery pipes 39, shown in the drawings, a circular row of 15 deposits of marshmallow will be made upon the top of each cake and each deposit of marshmallow will be individually coated by the chocolate or like confection.

It will be understood, of course, that the 20 valve mechanism whereby the flow of marshmallow and chocolate or like confections is controlled, will be actuated in accordance with the mechanism that advances the cakes to be coated in successive rows beneath the 25 depositing mechanism, as in the machine set forth in my said application Serial No. 807,851.

It is manifest that the precise details of construction above set out may be varied 30 without departing from the spirit of the invention and that features of the invention may be employed without its adoption as an entirely.

Having thus described my invention, what 35 I claim as new, and desire to secure by Letters Patent, is:—

1. In a machine of the character described, the combination with a plurality of receptacles for containing different materials to be deposited and with means for delivering 40 said materials from said receptacles, of groups of delivery pipes for the passage therethrough of material from one of said receptacles, mechanism for controlling the flow through said delivery pipes, means for permitting the flow of material from the other of said receptacles around the lower ends of said delivery pipes, valve 45 mechanism adjacent the lower ends of said delivery pipes for controlling the flow of said last mentioned material around the ends of said pipes, and means for automatically actuating said valve mechanism.

2. In a machine of the character described, 55 the combination with a plurality of receptacles for containing different materials to be deposited and with means for delivering said materials from said receptacles, of a series of concentrically arranged individual 60 delivery pipes for the passage therethrough of material from one of said receptacles, mechanism for controlling the flow through said delivery pipes, means for permitting the flow of material from the other of said 65 receptacles around the lower ends of said

delivery pipes, a series of individual valves for controlling the flow of said last mentioned material, and means for simultaneously operating said individual valves.

3. In a machine of the character described, the combination with a plurality of receptacles for containing different materials to be deposited and with means for delivering 70 said materials from said receptacles, of a series of concentrically arranged delivery pipes for the passage therethrough of material from one of said receptacles, valve mechanism for controlling the flow through said delivery pipes, a chamber through 75 which said delivery pipes pass, the bottom 80 of said chamber being provided with concentrically arranged discharge openings opposite the lower ends of said delivery pipes and at a slight distance therefrom, means for permitting the flow of material 85 from the other of said receptacles into said chamber, and around the lower ends of said delivery pipes, and valve mechanism for simultaneously controlling the flow of said last mentioned material through said discharge openings.

4. In a machine of the character described, the combination with a plurality of receptacles for containing different materials to be deposited, and with means for delivering 90 said materials from said receptacles, of a series of concentrically arranged delivery pipes for the passage therethrough of material from one of said receptacles, a casing 95 having upper and lower chambers and having discharge openings in its bottom, said delivery pipes leading from said upper chamber to said discharge openings, suitable channels for admitting material to said lower chamber, and valve mechanism within 100 said lower chamber for simultaneously controlling the flow of material therefrom through said discharge openings.

5. In a machine of the character described, the combination with a plurality of receptacles for containing different materials to be deposited and with means for delivering 110 said materials from said receptacles, of a series of groups of delivery pipes for the passage therethrough of material from one 115 of said receptacles, mechanism for controlling the flow through said delivery pipes, means for permitting the flow of material from the other of said receptacles around the lower ends of said delivery pipes, a series of groups of valves for controlling the flow of said last mentioned material, a series of valve carriers for actuating said groups of valves and means for simultaneously and automatically actuating said series of valve carriers.

6. In a machine of the character described, the combination with a plurality of receptacles for containing different materials to be deposited and with means for delivering 120 said materials from said receptacles, of a series of groups of delivery pipes for the passage therethrough of material from one 125 of said receptacles, mechanism for controlling the flow through said delivery pipes, means for permitting the flow of material from the other of said receptacles around the lower ends of said delivery pipes, a series of groups of valves for controlling the flow of said last mentioned material, a series of valve carriers for actuating said groups of valves and means for simultaneously and automatically actuating said series of valve carriers.

4
said materials from said receptacles, of a series of concentrically arranged delivery pipes for the passage therethrough of material from one of said receptacles, mechanism for controlling the flow through said delivery pipes, means for permitting the flow of material from the other of said receptacles around the lower ends of said delivery pipes, tubular valves surrounding

said delivery pipes for controlling the flow 10 of said last mentioned material, a series of valve carriers to which said tubular valves are connected, and means for actuating said valve carriers.

FREDERICK WESTERMAN.
